FIG. 5 is a left side view thereof;

FIG. 6 is a right side view thereof;

FIG. 7 is a perspective view thereof;

FIG. 8 is another perspective view thereof;

FIG. 9 is a front elevation view of a charging base for a portable media playback device, according to a second embodiment;

FIG. 10 is a rear elevation view thereof;

FIG. 11 is a top plan view thereof;

FIG. 12 is a bottom plan view thereof;

FIG. 13 is a left side view thereof;

FIG. 14 is a right side view thereof;

FIG. 15 is a perspective view thereof;

FIG. 16 is another perspective view thereof;

FIG. 17 is a front elevation view of a charging base for a portable media playback device, according to a third embodiment;

FIG. 18 is a rear elevation view thereof;

FIG. 19 is a top plan view thereof;

FIG. 20 is a bottom plan view thereof;

FIG. 21 is a left side view thereof;

FIG. 22 is a right side view thereof;

FIG. 23 is a perspective view thereof; and,

FIG. 24 is another perspective view thereof.

The dashed broken lines in the figures illustrate the portions of the charging base for a portable media playback device that form no part of the claimed design. The wavy dashed broken lines illustrate a symbolic break shown in the length of the cable of a charging base for a portable media playback device. The appearance of any portion of the article between the break lines forms no part of the claimed design.
